UNITED STATES PATENT OFFICE

GLENN H. BRITAIN, OF CHICAGO, ILLINOIS, ASSIGNOR TO THE ADLAKE COMPANY, OF CHICAGO, ILLINOIS, A CORPORATION OF ILLINOIS

WINDOW CONSTRUCTION

Application filed July 30, 1931. Serial No. 553,907.

It is a difficult matter to make the windows in railway cars and other rapidly moving vehicles weatherproof along the side edges of the sash, owing to the angle at which the air currents containing rain water, dust, cinders, etc. strike the outer forwardly facing edges of the guides when the car is in motion.

The object of the present invention is to provide improved means for weatherproofing such windows.

The weatherproofing means of the invention consists of two or more baffles which are mounted on the sash and guides in such relation to each other as to afford a labyrinth-like shield for the bearing surfaces of the sash and guides.

The baffles serve to break up the entering currents at their source, thereby preventing them from impinging directly against the bearing surfaces; they permit the water and other foreign matter to run out freely; they do not interfere in any way with the raising or lowering of the sash; and they are inexpensive to manufacture and apply.

While the foregoing statements are indicative in a general way of the nature of the invention, other objects and advantages will be apparent to those skilled in the art upon a full understanding of the construction, arrangement and manner of operation of the improved weatherproofing means.

In order that the invention may be readily understood, several different structural embodiments of the same are presented herein, but it will of course be appreciated that the invention is susceptible of embodiment in still other structurally modified forms coming equally within the scope of the appended claim.

In the drawings:

Fig. 1 is a fragmentary side view of a railway car, showing portions of two ordinary car windows equipped with the improved baffle arrangement;

Fig. 2 is a vertical section, taken on the line 2—2 of Fig. 1;

Fig. 3 is a horizontal section, taken on the line 3—3 of Fig. 2;

Fig. 4 is a perspective view of the baffle ar-

rangement shown in Figs. 1 to 3 inclusive; and

Figs. 5 to 8 inclusive are perspective views which show other structurally modified embodiments of the invention.

The window construction shown in Figs. 1 to 4 inclusive will first be described. In those views, a sash 10 is positioned between the post plates 11 of a window opening, with the side rails 12 of the sash disposed between outer and inner stops 13 and 14 on the post plates. The stops 13 and 14 form vertical guides in which the sash is adapted to slide in being raised or lowered. The inner stop 14—which may also serve as a curtain guide—is preferably made readily detachable, whereby to permit easy removal of the sash.

The sash 10 fits loosely between the stops 13 and 14, in order to permit it to slide freely up or down, and is pressed outwardly against the outer stop 13 when in either raised or lowered position by any suitable means. The particular means illustrated for this purpose consists of a rocker type lock 15 on the end 16 of the bottom rail 17 of the sash, which lock wedges against any one of several inclined seats 18 in a lock rack provided in the outer face of the inner stop 14, thereby forcing the lower portion of the sash outwardly. The upper portion of the sash is at the same time forced outwardly by an outwardly sprung-pressed anti-friction roller 19 which is located in a recess 20 in the inner stop 14 and bears against the inner face of the side rail 12.

The improved weatherproofing means which constitutes the subject matter of this invention consists of a vertically extending strip 20 which is attached to the side rail 12 of the sash and a second vertically extending strip 21 which is attached to the outer stop 13. The strip 20 has a flat attaching portion 22 which is secured against the outer face of the side rail 12, and has an outwardly projecting flange 23 along the exposed edge of the attaching portion. The strip 21 has a flat attaching portion 24 which is secured to the outwardly extending face of the outer stop 13, and has an offset inwardly projecting flange 25 along its inner edge, which flange

laps with the flange 23 of the other strip, preferably, though not necessarily, in slightly spaced relation thereto. The flange 23 extends into the groove 26 which is formed between the flange 25 and the face of the outer stop 13.

The above described construction provides a labyrinth-like double baffle arrangement for the protection of the bearing joint 27 between the outer face of the attaching portion of the strip 20 and the inner face of the outer stop 13, which arrangement effectively breaks the force of the entering air currents and prevents the same from impinging with full force directly against the joint 27. Any water or other foreign matter which passes the edge of the flange 25 will be deflected into the groove 26 behind the flange and will move freely down in the groove, leaving the same at the bottom through suitable drainage outlets. It will be noted that the attaching portion 22 of the strip 20 also functions as a wear strip for the side rail 12 of the sash.

25 The modified construction shown in Fig. 5 is likewise characterized by an outwardly projecting baffle flange 28 on the side rail of the sash, an inwardly projecting baffle flange 29 on the outer stop 30 in lapped relation to the flange 28 and a groove 31 behind the flange 29 for the reception of the flange 28, but in this embodiment of the invention the strip 32 which carries the flange 29 is provided with a double bend in order to form 35 the groove and is attached to the inner face 33 of the outer stop 30 instead of to the outwardly extending face of the same.

In the construction shown in Fig. 6, the above described arrangement is reversed. 40 The strip 34 on the side rail of the sash is provided with two outwardly projecting flanges 35 and 36, with an abrupt groove 37 between the flanges, and the strip 38 on the outer stop is provided with an offset flange 45 39 which extends into the groove 37. The flange 35 on the strip 34 extends into the groove 40 which is formed behind the flange 39 by the offsetting of the latter. 50 The strip 34 is secured to the side rail by a 55 combination of rivets and adhesive cement. The strip 38 is secured to the outer stop by a combination of rivets and adhesive cement. 60 To close the gap between the flange 35 and the flange 39, a thin metal strip 41 is applied to the outer stop 30, the strip 41 being bent around the flange 39 and secured to the outer stop 30 by adhesive cement. 65

In Fig. 7, two light gauge strips 41 and 42 are applied—one over the other—to the side rail of the sash, and such strips are provided with outwardly bent flanges 43 and 44, which flanges terminate in reversely bent 70 resiliently yieldable spring edges 45 and 46. The edges 45 and 46 converge inwardly into substantial contact with each other, and bear resiliently against the opposite sides of an inwardly projecting flange 47 which is 75 formed as an offset on a strip 48 which is fastened to the outer stop. The closed groove 49 which is formed between the edges of the flanges 43 and 44 will effectively stop any air, water or other foreign matter which 80 happens to get past the edge 46.

In Fig. 8, the sliding joint 50 between the outer face of the side rail of the sash and the inner face of the outer stop is not protected by any outside baffle arrangement. Instead, 85 a flange 51 is formed on the outer edge of the inner stop behind the edge of the rail, and a groove 52 is formed in the edge of the rail for the reception of the flange 51.

I claim:

In window construction, the combination with a vertically slidable sheet metal sash, vertical guides at the sides of the sash, and means for pressing the sash outwardly against the outer walls of the guides when the sash is closed, of flat wear strips secured to the outer walls of the side rails of the sash within the guides in direct opposition to the outer walls of the guides for extended surface contact with the latter, said wear strips being provided beyond the edges of the outer walls of the guides with outwardly projecting flanges, and cover strips secured to the guides and provided beyond the edges of the outer walls of the guides with offset flanges which extend about the outwardly projecting flanges on the wear strips to provide labyrinth-like shields for the contact portions of the wear strips when the sash is closed.
